UNITED STATES PATENT OFFICE.

JOSEPH E. LOCKWOOD, OF BRIGHTON, CANADA.

COMBINATION-LOCK.

SPECIFICATION forming part of Letters Patent No. 567,146, dated September 8, 1896.

Application filed June 28, 1895. Serial No. 554,320. (No model.)

To all whom it may concern:

Be it known that I, JOSEPH ELLISON LOCKWOOD, of Brighton, in the county of Northumberland, and Province of Ontario, Canada, 5 have invented certain new and useful Improvements in Combination Door-Locks; and I hereby declare that the following is a full, clear, and exact description of the same.

This invention relates to that class of inventions known as "combination door-locks," and it relates more particularly to the construction of a door-lock which can be readily fitted to any door and operated without the employment of a key, and the object of my 15 invention is to so arrange the several parts of the lock that they can each and all be easily, readily, and cheaply manufactured and easily assembled and operated.

My invention consists of a certain combination and arrangement of parts hereinafter more fully set forth, and more particularly pointed out in the claims.

In the drawings, Figure 1 is a perspective view of the lock with the case partially removed, showing the locking-latch shot forward and the several parts in their normal or starting position preparatory to being operated by the tumbler-setting mechanism. Fig. 2 is a similar view showing the tumblers 25 set and the various parts in position to permit of the operation of the locking-latch. Fig. 3 is a view of the tumblers. Fig. 4 is a view of the cam for operating the locking-latch. Fig. 5 is a view of the retaining-dog. Fig. 6 is a view of one of the tumbler-operating dogs and the slide to which it is connected. Fig. 7 is a view of the lower part of 30 the lock-case, showing the arrangement of the bell-crank levers for operating the tumblers. Fig. 8 is a view of the stopper with its respective arm to lock the tumbler-operating dogs. Fig. 9 is a perspective view of the knob-plate with its locking-tumbler and slide. Fig. 10 is a detail vertical section taken adjacent to a set of the bell-crank levers and showing a plunger for 35 operating one of the levers.

Like letters of reference refer to like parts throughout the specification and drawings. 50 The lock-case A is of a substantially rectangular shape and consists, essentially, of two sides *a a*, a top *a'*, and a bottom *a''*, a front

or latch plate *a'''* and an end *a''''*. Within the lock-case A, at or about the middle thereof, is a hollow thimble B, rigidly connected to 55 one of the sides *a*. Loosely mounted on the thimble B are a series of circular tumblers C C' C''. The periphery of the rim of the tumbler C is serrated or provided with a series of ratchet-teeth D for the purpose hereinafter set forth, while the side face of the tumbler C has stamped or engraved on it an indicating-dial E; that is, the side face of the tumbler C is divided into an equal number of parts, each numbered and corresponding, 65 respectively, with the number and pitch of the ratchet-teeth D.

Projecting from the side face of the tumbler C, between the indicating-dial E and the bearing F for the tumbler, is an annular 70 flange G, concentric with the rim of the tumbler. The flange G is so beveled that the diameter of the top of the flange is greater than the bottom of the flange. Encircling the flange G is a divided ring H, correspondingly 75 beveled and sprung on the said flange G. The space between the adjacent meeting ends *h h'* of the divided ring H is sufficient to receive its respective retaining-dog. Between the flange G and the bearing F is a segmental 80 slot I, concentric with the rim of the indicating-dial E. Through the segmental slot I passes a pin J, secured to the side *a* of the lock-case A. The pin J is parallel with the thimble B and arrests the tumbler C by coming into contact with the end *i* of the segmental slot I when the tumbler C has completed its movement in one direction; that is, when throwing off the combination to lock 85 the locking-latch, in order that the said tumbler can be held in its proper normal or starting position. Engaging with the ratchet-teeth D of the tumbler C is a spring-operated dog K, pivotally connected to a horizontally-disposed slide L. The dog K is provided 90 with a shoulder *k''*, which abuts against a stop *j*, connected to the bottom *a''* of the case and so arranged as to arrest the return movement of the slide and depress the engaging end of the dog against or into the slide L 95 when the said slide is in its return position, to allow of the free return movement of the tumbler C to its normal or starting position. Formed in the slide L is a socket *l*, and with-

in the socket l is a spring l' , which bears against the inner side of the dog K and throws the engaging end of the dog K outwardly from the slide L when the shoulder k'' is not 5 in engagement with the stop J . Connected to the slide L is a projection M , against which bears one end n of the bell-crank lever N , pivotally connected to the bottom a'' of the lock-case A . The opposite end n' of the bell-crank 10 lever N is operated by a plunger O . The depression of the plunger O displaces the end n' of the bell-crank lever N and causes the opposite end n to move the slide L and cause the dog K to rotate the tumbler C the distance of one tooth. By repeatedly operating the plunger O it is possible to move the tumbler C any number of spaces or predetermined 15 number of spaces, as may be required. To enable the slide L to be operated from either 20 side of the lock, I mount on the same pivot-pin P two bell-crank levers N N' , both operating on the same projection M and on the same side of it, in the manner hereinbefore described, and both of the bell-crank levers 25 N N' , operated by similar plungers O . To cause the sharp return of the slide to its normal or starting position, I provide the plunger O with a spring Q to throw the plunger out of engagement with the end n' of its respective bell-crank lever, and I provide the slide 30 L with a coiled spring R to throw the slide in the opposite direction to its movement by the bell-crank lever. Pivotally connected to the case A is a lever S , carrying a series of dogs 35 T T' T'' . Carried by the lever S at the point S' is an arm U , having a head V , which engages with the ends of the slides L L' L'' when the lock is unlocked, thereby serving 40 as a stop for said slides and to keep them in proper alinement.

When the lock is locked and requires to be operated by the plungers O before it can be opened, it is necessary that the levers S and arm U be moved to remove the head V 45 from engagement from the ends of the said slides. This is accomplished in the manner hereinafter set forth. Mounted on the top of the tumbler C is a tumbler C' , and mounted on the tumbler C' is a third tumbler C'' . The 50 tumblers C' C'' are similarly constructed to the tumbler C and are operated by dogs K' K'' , connected to the slides L' L'' , similar in all respects with the slide L and operated in a similar manner. The divided ring H' for 55 the tumbler C' is provided between its adjacent meeting ends with a notch or space k' , while the divided ring H'' is provided with a similar notch or space k'' , the notches or spaces k' k'' corresponding in size and purpose 60 with the notches or spaces h'' . By setting the notch or space of any one of the divided rings over any particular division on the indicating-dial it will be necessary to depress the plunger O , operating on the tumbler, the 65 number of times indicated by the numeral on the said division, in order that the said tumbler can be rotated a distance equal to that

number of teeth; that is, if the notch or space is set opposite the division on the indicating-dial marked "7" it will be necessary to operate the respective plunger O seven times, in order that the tumbler can be moved a distance equal to the distance of seven teeth. Bearing on the back of the lever S and against the top a' of the lock-case A is a spring W 70 to throw the lever S toward the tumblers C C' C'' , in order that the dogs T T' T'' may enter their respective notches or spaces h'' k' k'' , respectively, when the said notches or spaces are in alinement. Revolving on the 75 top of the thimble B is a cam X , which at a certain part of its revolution engages with a key-bit Y , pivotally connected to the locking-latch Z . In the top of the key-bit Y is an elongated slot A' , into which projects a 80 pin A'' , extending from the side of the lever S . When the dogs T T' T'' are bearing against the periphery of their respective tumblers C C' C'' , the lever S is moved into the position shown in Fig. 2 of the drawings and 85 displaces the key-bit Y to prevent its operation by the cam X . Connected to the case A is a spring B' to shoot forward the locking-latch Z . Formed centrally through the cam X is an opening D' , and surrounding the 90 opening D' is a collar D'' . The collar D'' fits into the thimble B , and the inner face of the collar D'' is fitted to engage with a knob-spindle B'' , passing through the door and lock. On the inside of the door and surrounding the knob-spindle B'' is a knob-plate 95 E' , and within the knob-plate E' is a locking-tumbler E'' , the periphery of which is provided with three notches e e' e'' . 100

Working within the knob-plate E' is a sliding bar F' , provided on its under side with two lugs G' G'' . The lugs G' G'' are a sufficient distance apart to permit of the locking-tumbler E'' being turned in either direction without coming into engagement with any of 105 the notches when the sliding bar F' is in such a position as to place both of the said lugs G' G'' beyond the periphery of the locking-tumbler E'' . When the sliding bar F' is so moved as to bring the lug G' into engagement with the notch e , the rotary movement of the tumbler E'' and the spindle B'' is limited to allow of the locking-latch being released and shot forward to a sufficient extent to permit of the opening or closing of the 110 door without throwing off the combination. When the lug G' is within the notch e , it is necessary for the dogs T T' T'' to be in their respective notches and their respective setting-rings, in order that the operation of the 115 locking-latch can be accomplished. By allowing the locking-tumbler E'' and the knob-spindle B'' a limited movement it is possible to turn the knob-spindle sufficiently to release the locking-latch and to allow of the return of the knob-spindle a sufficient distance to shoot forward the locking-latch without 120 allowing the cam to throw off the combination. To lock the locking-latch in its re- 125

105

110

115

120

125

130

leased position, the sliding bar F' is moved to bring the lug G" into engagement with the notch e', and to lock the locking-latch when shot forward the sliding bar F is moved to bring the lug G" into such a position that it will enter the notch e". When the lug G" is in either of the notches e' e", it is utterly impossible to revolve the knob-spindle to any extent whatever, and consequently the locking-latch is locked either in its released or its shot position. The cam X is provided with a projecting lug or pin x, which is adapted to come into contact with the end i' of the segmental slot I in each of the tumblers C C' C" to return the tumblers to their normal or starting position when the combination has been thrown off.

The operation of the lock is as follows: The revolution of the cam X in the direction indicated by arrows in Fig. 2 of the drawings causes the pin x to return the tumblers C C' C" to their normal or starting position. Assuming that tumbler C is set on "7," tumbler C' is set on "3," and tumbler C" is set on "10," it will be necessary to depress the plunger O seven times to operate the bell-crank lever N a corresponding number of times to move the tumbler C forward a distance of seven tooth-spaces, in order that the notch in the setting-ring will be brought opposite its respective retaining-dog. The tumbler C' will be moved a distance equal to three tooth-spaces to bring the notch in its respective setting-ring opposite its respective retaining-dog, and the tumbler C" will be moved forward a distance of ten tooth-spaces for the same purpose. When the tumblers have been moved forward their respective distances, the notches in the respective setting-rings will be in alinement with the retaining-dogs, and the retaining-dogs will enter their respective notches in the setting-rings and securely hold the tumblers in their set position until after the locking-latch has been operated and the combination of the tumblers has been thrown off by the action of the pin or lug x of the cam X. It has hereinbefore been stated that the key-bit Y is provided with an elongated slot A', into which projects a pin A", extending from the top of the lever S. As the lever S carries the retaining-dogs the entry of the retaining-dogs into their respective notches in their respective setting-rings permits the spring W to throw the lever S toward the periphery of the tumblers to bring the hook-shaped part y of the key-bit Y into engagement with the hook-shaped part x' of the cam X to allow of the cam x drawing rearwardly the said key-bit. As the key-bit Y is connected to the locking-latch Z, the said key-bit during its rearward movement carries with it the locking-latch Z. When the pressure on the cam X is released, the spring B' shoots forward the locking-latch Z, and the cam X is turned by the hand of the operator in the direction opposite to the releasement of the locking-latch to bring the tumblers

again into alinement, the operation of the plungers being again repeated when it is necessary to bring the tumblers C C' C" into 7° alinement to allow of the releasing of the locking-latch.

Having thus fully described my invention, what I claim as new, and desire to secure by Letters Patent, is—

75

1. A combination-lock, comprising a suitable casing, a sliding bolt therein, a key-bit pivotally connected to said bolt and provided with a longitudinally-arranged slot, a series of rotatable tumblers, a series of spring-actuated slides, a spring-actuated dog in each slide to move the tumblers, a stock in the casing to depress the dogs, a lever S, pivotally supported in the casing and formed with dogs on its free end, and having a lug or pin 85 on its side to engage in the slot of the key-bit, an arm carried by said lever, and formed with a head to engage the tumbler-slides, a cam to engage the key-bit, and plungers to operate the tumbler-slides, as specified.

90

2. A combination-lock, comprising a casing formed or provided with a hollow thimble, a series of circular tumblers journaled on the thimble, and having segmental slots adjacent to the thimble, and provided with ratchet-teeth on their periphery, and the outer tumbler formed with an annular beveled flange, divided rings on the flange, a fixed pin projected through the segmental slots of the tumblers, a cam journaled on the thimble and formed with a notch, a sliding bolt in the casing, a key-bit pivoted to the bolt, and formed with a catch to engage the notch of the cam, a lever S, formed with dogs on the free end, slides under the tumblers formed with lugs, spring-dogs pivoted in slides to engage the tumblers, bell-crank levers to engage lugs on the slides, a lever between the lever S and the slides, formed with a head to lodge against the end of the slides, and plungers to operate the bell-crank levers, substantially as set forth.

100

3. A combination-lock, comprising a lock-casing, a locking-latch within the casing, a plurality of rotatable tumblers within the casing, an adjustable setting-ring formed with a notch, carried by each tumbler to vary the combination of the lock, a lever formed with dogs on its free end to engage the notches of the setting-rings, a key-bit pivoted to the locking-latch, and arranged to be lifted by the lever carrying the dogs on its free end, and a rotatable cam to engage the key-bit, substantially as described.

115

4. In a combination-lock, the combination with the series of suitably journaled tumblers formed with a segmental slot adjacent to their bearings, and a pin fixed to the casing and projected into the segmental slot, whereby the rotation of the tumblers is limited, substantially as specified.

120

5. In a combination-lock, the combination with the rotatable tumblers and mechanism for rotating them, of a sliding bolt, a key-bit

125

130

pivoted to the bolt and formed with a catch, a cam on the spindle of the tumblers to engage the catch of the key-bit, and a lever formed with dogs on its free end to engage 5 the tumblers and when disengaged therefrom to hold the key-bit from engagement with the cam, substantially as set forth and described.

6. In a combination-lock the combination 10 of the locking-latch, the locking-latch-operating tumblers, actuating mechanism and knob-spindle, of a lock-case, a notched locking-tumbler within the lock-case, and a slide provided with two lugs adapted when in a cer- 15 tain position to allow of the free revolution

of the knob-spindle and locking-tumbler, and one of said lugs adapted to enter one of the notches in the locking-tumbler to allow of a limited movement on the part of the locking-tumbler, and the other lug adapted to be 20 moved into either one of the remaining notches to lock the locking-latch either in its released or shot positions, substantially as specified.

Brighton, May 27th, A. D. 1895.
